EXPANDABLE HOLDER FOR A PAIR OF SPECTACLES

Helen G. Rafshoon, 3547 Buford Highway NE., Apt. G,
Atlanta, Ga.

Filed Dec. 14, 1970, Ser. No. 26,434

Term of patent 14 years

Int. Cl. D16—06

U.S. Cl. D57—1

FIG 1

FIG. 1 is an elevational view of an expandable holder for a pair of spectacles showing my new design.

FIG. 2 is a right side elevational view thereof.

FIG. 3 is an enlarged fragmentary view of the holder in expanded condition.

The expandable holder is symmetrical in construction and those sides not shown are identical to those shown.

I claim:

The ornamental design for an expandable holder for a pair of spectacles, substantially as shown and described.
